UNITED STATES PATENT OFFICE

AUGUST JIPP, OF BERLIN-SPANDAU, GERMANY, ASSIGNOR TO SIEMENS & HALSKE, AKTIENGESELLSCHAFT, OF SIEMENSSTADT, NEAR BERLIN, GERMANY, A CORPORATION OF GERMANY

METHOD OF AND MEANS FOR RECEIVING TELEGRAPHIC SIGNALS

Application filed November 30, 1928, Serial No. 322,624, and in Germany August 6, 1927.

Application filed in Germany, August 6, 1927.

It is known from practical telegraphy work, especially in the case of radio signalling that the incoming signals are often mixed with disturbances, for instance, of atmospheric origin and nature, whereby the received signals are often rendered unintelligible. It is also known that disturbances of relatively high frequency, say, down to around 1.6 times the dot frequency utilized in telegraphic signalling, can be eliminated by the aid of filter circuits or parallel condensers.

According to this invention these disturbances (including the dot currents) down to about 1.6 times the dash frequency, i. e., to about 0.5 times the dot frequency, are to be eliminated.

The invention is based upon the fact that the Morse signals chiefly used in radio work consist of a continuous alternating current (Fig. 1, curve I) in which certain waves are suppressed for the formation of dots and dashes, and that the characteristic distinction between the signs inheres only in such suppressions, i. e., the dashes and spaces, but not in the uninterrupted alternating current. Still, the latter constitutes a valuable auxiliary, a pattern, as it were, whereby the signals are made more readily readable.

This unchanging pattern or stencil consisting of the alternating current, according to the invention, is locally added again to the text, freed from disturbances and dots. All that is necessary is to know the frequency of this alternating current. The latter may be of pre-arranged value, in which case it is kept constant at both ends, or else it can be ascertained with any desired accuracy from the incoming signals in spite of the presence of disturbances or stray. It can then be used for the synchronization of a pendulum or of a revolving machine adapted to generate an alternating current pattern-fashion with accuracy, free from disturbance. Finally the generated alternating current is combined with the incoming currents which have been freed from dot and stray frequencies.

The accompanying drawing shows an exemplification of the basic idea of the invention for better understanding. In the drawing Fig. 1 shows the shape of the current in the different parts of the circuit arrangement and the desired resultant composition to act as the final current upon recorder apparatus and Fig. 2 is a circuit arrangement for carrying out the steps shown in Fig. 1.

Referring to Fig. 1 the incoming current, after rectification, has the shape of curve I, the dot frequencies suppressed in signalling being here shown by dotted lines. Curve II of Fig. 1 shows the form of this current after having passed a filter circuit in which all stray and dot frequencies are eliminated, with the latter being indicated by the dash lines.

The shape of the current in the oscillation circuit or in the filter being tuned to the dot frequency and connected in parallel relation to the filter circuit is shown in by curve III. The feebly damped circuit is impelled every time a dot signal comes in. This current is made to produce, for instance, by the aid of a synchronous motor and a contact disk, a new current of the same frequency, but of sharply rectangular form as shown in curve IV. The current shown in graph IV then is brought to conjointly act with the incoming current II whose path is closed by way of the filter upon a recording device or the like.

Currents II and IV combinedly result in a current having a shape as shown in curve V. If in this current, say, by current-limiting means, the outer jags or peaks are cut off, for instance, along the lines indicated by the dashes, or, if the recorder apparatus is provided with a mechanical stop which corresponds to these current limits, there finally results a current of the kind shown in graph VI which corresponds to the current signals recorded by the recorder or the like.

Fig. 2 by way of example shows the new circuit arrangement built according to this invention. The incoming signal current is first fed to a rectifier *g* to which there is connected, on the one hand, a filter *f* adapted to suppress the dot and stray frequencies, and,

on the other hand, an oscillation circuit *k* which is tuned to the dot frequency. Connected with said oscillation circuit *k* is the stator of a synchronous motor *m* whose rotor 5 drives a contact disk *s*. The latter, owing to alternate change of polarity of two batteries *b* produces sharply outlined rectangular current impulses of dot frequency in a circuit brought to recording apparatus *a*, and these 10 current impulses are combined with the incoming currents having passed through the filter and being of dash frequency, thus resulting in signals of the desired form.

What is claimed is:—

- 15 1. The method of receiving signals which includes filtering out from the incoming signal currents dot frequency and stray frequency currents, and combining the remainder of the incoming signal currents with 20 a locally generated alternating current of dot frequency and predetermined shape whose frequency is made to depend upon the dot frequency of the incoming signal.
2. The method of receiving radio telegraphic signals consisting of a carrier modulated by dots of a predetermined dot frequency and dashes obtained by the suppression of dot frequency energy which includes rectifying the incoming signal, filtering from 30 the rectified signal dot and stray frequency currents, generating a current of the dot frequency and of a predetermined shape, and combining the generated current and the remainder of the incoming rectified signal current.
- 35 3. A receiver comprising a filter for filtering from a received rectified signal currents of dot and stray frequencies, a generator for generating an alternating current, means for 40 combining the generated alternating current and the currents passed by the filter and means for recording the combined currents.
4. The method of receiving radio telegraphic signals consisting of a carrier modulated by dots of a predetermined dot frequency and dashes obtained by suppressing dots, which includes, rectifying the incoming signal, separating dot and dash frequency energy from the rectified energy, utilizing the 50 separated dot frequency energy to generate locally, square wave form energy, combining the square wave form energy with the filtered dash frequency energy, limiting the combined energy, and translating the limited energy.

In testimony whereof I affix my signature.
AUGUST JIPP.
